United States Patent [19]

Gamm

[11] Patent Number: Des. 281,925

[45] Date of Patent:  Dec. 31, 1985

[54] BOOT WITH TONGUE POCKET

[75] Inventor: Robert J. Gamm, St. Louis County, Mo.

[73] Assignee: Kanagroos U.S.A., Inc., St. Louis, Mo.

[] Term: 14 Years

[21] Appl. No.: 500,170

[22] Filed: Jun. 1, 1983

[52] U.S. Cl. D2/275; D2/314;
D2/274
